DESIGN FOR A SOAP DISPENSER

Charles W. Hoppe, Buffalo, N. Y.

Application November 19, 1945, Serial No. 123,900

Term of patent 7 years

(Cl. D4—3)

To all whom it may concern:

Be it known that I, Charles W. Hoppe, a citizen of the United States, residing at Buffalo, in the county of Erie and State of New York, have invented a new, original, and ornamental Design for a Soap Dispenser, of which the following is a specification, reference being had to the accompanying drawing, forming part thereof.

In the accompanying drawing:

Fig. 1 is a perspective view of the soap dispenser embodying my new design.

Fig. 2 is a side elevation thereof, the view from the opposite side being substantially identical.

Fig. 3 is a front elevation thereof.

Fig. 4 is a top plan view thereof.

I claim:

The ornamental design for a soap dispenser, as shown.

CHARLES W. HOPPE.
